UNITED STATES PATENT OFFICE.

FRED C. AREY, OF CHICAGO, ILLINOIS, ASSIGNOR TO HORLICK'S MALTED MILK COMPANY, OF RACINE, WISCONSIN, A CORPORATION.

BOTTLE-TOPPING MEANS.

Application filed July 18, 1921. Serial No. 485,573.

To all whom it may concern:

Be it known that I, FRED C. AREY, a citizen of the United States, residing at Chicago, in the county of Cook and State of Illinois, have invented certain new and useful Improvements in Bottle-Topping Means, of which the following is a specification.

My invention has reference to the sealing of bottles or jars and relates particularly to the means for affixing a label or seal to the upper edge of the bottle neck.

It is customary to put up certain materials, as for example malted milk, in large bottles or jars which are closed by a cover or cap having a threaded or similar connection with the bottle, and it is desirable to have some means in addition to the cover for sealing the jar, this being accomplished with my invention by securing a label or seal of paper or other suitable material to the upper edge of the bottle neck.

The principal objects of my invention are to provide an improved means for sealing a bottle or jar; to apply a label or seal of paper or similar material to the upper edge of the bottle neck so that it will adhere securely thereto; to affix the seal to the mouth of the jar or bottle by a gum or adhesive; to withdraw the seal applying device so as to avoid displacement of the seal; and in general, to provide an improved machine of simple form, which is capable of securely affixing a seal of paper or similar material so as to close the mouth of a jar or bottle.

On the drawings—

Fig. 1 is a front view of a machine embodying my improvements, portions thereof being broken away and shown in section so as to disclose details of construction;

Fig. 2, a side view of the machine shown in Fig. 1;

Fig. 3, a top view of the sealing head with the parts which support same shown in section;

Fig. 4, a vertical sectional view of the sealing head on the line 4—4 of Fig. 3, showing the head in the initial position of applying a seal to a jar;

Fig. 5, a similar view showing the head in the final position of applying a seal to a jar;

Fig. 6, a sectional view on the line 6—6 of Fig. 5;

Fig. 7, a bottom view of a seal applying head with the parts in the position shown in Fig. 4;

Fig. 8, an enlarged sectional view on the line 8—8 of Fig. 1;

Fig. 9, a detail view of the stripper cam;

Fig. 10, an enlarged sectional view of the cam mechanism taken on the line 10—10 of Fig. 2, and

Fig. 11, a sectional view on the line 11—11 of Fig. 10.

Referring to the drawings the reference numeral 1 indicates an upright post which is supported in any suitable manner and carries the various parts of the sealing device. The machine illustrated is of a duplex or double acting type comprising two heads indicated as a whole at 2, which reciprocate alternately toward a pair of bottle supports 3, which are carried upon the opposite ends of a cross arm or bracket 4, which has an intermediate portion telescoped on the post 1 and secured at the desired elevation by set screws 5.

Each of the bottle supports 3 comprises a cup-shaped housing 6, which is secured on the upper end of a sleeve 7, the latter having a reduced extremity 8 which fits in an aperture provided therefor at the outer end of the cross arm 4 so as to hold the bottle support in proper position with reference to the sealing head. The housing 6 is telescoped by an inverted cup-shaped casing 9 which has a plate 10 secured to the upper end by a threaded connection as shown, or in any other convenient manner, and the plate 10 has a band 11 extending upwardly around the edge to hold a block 12 of wood upon the upper face of the plate 10. A spring 13 is interposed between the closed ends of the housing 6 and casing respectively which are held against undue separation by a bolt 14 which has the headed end engaged with and countersunk in the upper face of the end wall of the cup-shaped casing 9 and the stem inserted down through the spring and sleeve 7 and provided with a pair of lock nuts 15 on the lower end which may be adjusted to regulate the compression of the spring 13.

The bottles or jars 16 which this machine is designed to seal are large ones such as are commonly employed to contain malted milk

105

and the wooden blocks 12 are large enough to accommodate one of these bottles. To facilitate placing the bottles in proper position on the supports 3, there is a cross arm 5 or disc 17 on the post 1 which projects a short distance over each of the supports 3 and is provided with an arcuate plate 18 at each end having a facing 19 of leather or similar material which fits the exterior of the bottle and is adapted to have the latter engaged thereagainst preparatory to the performance of the sealing operation.

Secured to the upper end of the post 1 is a large bracket 20, which has a pair of horizontally spaced bearings 21 in which a drive shaft 22 is mounted with a pulley 23 fixed thereon between the bearings 21 and connected by the belt 24 to any suitable source of power. This bracket 20 at opposite sides of the post 1 and directly above the bottle supports 3, has vertically apertured hubs 25 each of which supports a yoke shaped frame 26, which has an arcuate flange portion 27 at the inner end engaged over the corresponding bearing member 21 of the main bracket 20 and secured thereto by one or more cap screws 28.

A separate countershaft 29 is mounted at the upper end of each yoke-shaped frame 26 in spaced bearings 30, and each of these shafts has a spur gear 31 at the inner end meshing with a pinion 32 on the main shaft 22 whereby the countershafts are operated at a lower rate of speed than the main shaft. Each yoke frame 26 is formed at the bottom with a pair of spaced flanges 33, which extend between and connect the arms of the yoke and these flanges are connected together at a point substantially between their ends by an integral transverse web 34 which is recessed at opposite sides to form vertical dove-tailed guide-ways 35 and 36, the latter of which is disposed directly above the hub 25. For connecting each frame 26 with the hub of the bracket 20 a combined key and bushing is employed having a dove-tailed head 37 engaging in the lower end of the dove-tailed guide-way 36 and a sleeve portion 38 fitting in the opening 39 in the hub 25 so as to lock the frame 26 and hub 25 together. A plunger shaft 40 extends down through the sleeve 38 and also through a bearing 41 in the end of a cross arm 42 which is adjustably secured on the post 1 by set screws 43 and this shaft has the sealing head 2 mounted on the lower end thereof below the cross arm 42. The upper end of the plunger shaft 40 is threaded as at 44 and engaged in a threaded socket in the lower end of a dove-tailed block 45, which fits in the dove-tailed guide-way 36 of the bracket 26 and this block is provided at one side with a pin 46 carrying an anti-friction roller 47, which engages the periphery of a cam 48 on the countershaft 29. This cam

serves to force the plunger shaft 40 downwardly to effect the sealing operation and has the roller 47 held thereagainst by the elevating spring 49 which surrounds the shaft 40 between the hub 25 and the bearing 41 and has the lower end bearing against the latter and the upper end bearing against a collar 50, which is secured on the shaft 40 by the pin 51.

Secured to the lower end of the shaft 40 by the threaded connection 60 or in any suitable manner is a shank 52 having four radially disposed sets of pivot lugs 53 and each pair of lugs has a pivot pin 54 extending therebetween and supporting a finger or lever 55, each of which above the pivot 54 is engaged by a thrust spring 56 seated in a socket 57 in the shank 52 so as to normally throw the upper ends of the fingers outwardly and the lower ends inwardly. The lower end of the shank 52 is formed with a reduced externally threaded extension 58 upon which a flat ring 59 is engaged so as to come flush with the lower face of the extension 58 and form therewith a smooth face of a little larger diameter than the upper end of the bottle or jar to which the seal is to be applied. Each of the fingers 55 has an arcuate plate 61 on the lower end which extends substantially 90° around the ring 59 and has the lower face substantially in the same plane as the lower face of the disc 59 when the lower ends of the fingers 55 are in the innermost position. For securing the plates 61 onto the fingers 55 each plate has a notch 62 in the upper face midway between the ends into which the lower end of the finger 55 fits and there is a cap screw 63 extending through the plate 61 and threaded into the lower end of the finger 55. A rubber cushioning element 64 is secured to the under face of each plate 61 and extends inwardly beyond the plate, as shown particularly in Figure 4, so as to project under the ring 59 when the fingers 55 are in the normal position and thus provide a cushion between the disc 59 and the upper edge of the bottle neck for pressing the edges of the seal 65 into sealing engagement therewith when the sealing head is forced downwardly. These rubber segments 64 may be secured to the plate 61 in any convenient manner as for example, by a number of cap screws 66, which have the head countersunk in the rubber segments 64 and the threaded stems engaged in threaded apertures in the plates 61.

The fingers 55 are designed to be rocked on their pivots 54 after the seal is pressed onto the bottle or jar so as to move the rubber segments 64 outwardly beyond the edges of the seal to prevent displacement of the seal when the head recedes and for effecting this result, a collar or stripper ring 67 is slidably arranged on the shank 52 and

has a beveled internal face 68 engaging the upper ends of the fingers 55 and adapted when elevated to permit the upper ends of the fingers to swing outwardly under the influence of the springs 56 and the lower ends accordingly to swing inwardly and position the inner edges of the rubber segments 64 under the periphery of the ring 59. When, however, the ring 67 is moved downwardly over the ends of the fingers 55 the beveled face 68 forces the upper ends of the latter inwardly thereby swinging the lower ends with the plates 61 and rubber segments 64 carried thereby outwardly to the position shown in Figure 5.

To control the operation of the ring 67 there are pins 69 extending laterally therefrom at each side which are connected by elevating springs 70 to pins 71, which project outwardly from the base of the yoke bracket 26, and the pins 69 are also connected by links 72 with a block 73 in the guideway 35 and said block has a pin 74 projecting laterally therefrom and carrying an anti-friction roller 75, which engages against the periphery of the cam 76 on the countershaft 29. To confine the movement of the links 72 to an up and down direction the block 73 is bifurcated at a point above the pin 74 so as to straddle the shaft 29 and there is a cross plate 77, which extends between and is secured to the upper extremities of the said parts above the shaft 29.

In the operation of this device the bottle is placed on the support 3 with a seal in place thereon and the sealing head 2 projected downwardly with the parts maintained in the position shown in Figure 4, so that the inner edges of the rubber segments 64 extend under the ring 59 and press the edges of the seal against the mouth of the bottle. To effect the depression of the head and maintain the parts as shown in Fig. 4, it is necessary for the shank 52 with the fingers 55 thereon and the ring 67 to move downwardly in unison and to accomplish this movement the cams 48 and 76 each have a corresponding rise 78 and 79 respectively leading up to corresponding arcuate faces 80 and 81 respectively, which act simultaneously upon the rollers 47 and 75 to depress the shaft 40 and the links 72, thereby moving the entire sealing head 2 downwardly as a unit and the radius of these faces 80 and 81 is such that the head 2 is caused to force the bottle 16 downwardly a very short distance so as to compress the spring 13 and afford a yielding pressure for clamping the edges of the seal 65 against the mouth of the bottle. The cam faces 80 and 81 are made somewhat long so as to hold the seal 65 under pressure a sufficient length of time to allow the adhesive to set, after which the pressure on the bottle is released sufficiently to relieve

the compression of the spring 13 and permit elevation of the bottle support to or substantially to the normal position, this being effected by a decrease in the radius of the cam 48 at 82 which continues to the point 70 83 where the cam is cut away to a short radius as shown at 84, which permits the spring 49 to elevate the shaft 40 and head 52 thereon. At the time that the pressure on the bottle is released by the decrease on the radius of the cam at 82 the ring 67 is forced downwardly so as to engage the upper ends of the fingers 55 and force the lower ends of the latter radially and thus withdraw the rubber segments 64 outwardly 80 over the edges of the seal 65 to the position shown in Fig. 5, so as to avoid displacement of the seal when the sealing head 2 is elevated. The head 2 is not elevated sufficiently 85 during the time that the cam portion 82 85 engages the roller 47 to withdraw the rubber segments or cushioning elements 64 from the seal 35, but these cushioning elements 64 remain in contact with the seal so that they have a rubbing contact with the seal, 90 particularly the edge portions thereof, as they are withdrawn radially over the seal by the depression of the ring 67. For operating the ring 67 to withdraw the segments 64, the cam 76 is formed at 85 with 95 an abrupt rise or projection, which forces the roller 75 and parts to which it is connected downwardly while the parts controlled by the cam 48 remain inactive and at a point substantially in the same radial 100 plane with the final extremity of the cam face 82, the face of the cam 76 recedes inwardly as at 87 to a face 88 of a radius corresponding to the face 84 of the cam 48, which permits the springs 70 to withdraw the ring 67 from the upper ends of the fingers 55 and return the fingers to the position shown in Fig. 4 and at the same time co-operates with the cam 48 and spring 49 to return the head 2 to the elevated position to permit removal of the sealed bottle and insertion of another bottle, which is to be sealed.

The seals employed may be of paper or any other suitable material and are preferably gummed on the entire undersurface although they may, if desired, be provided merely with a ring of adhesive material on the under face around the edge of suitable width to extend over the upper edge of the bottle mouth. The upper edge of the bottle neck is preferably moistened and the seal laid on the wet surface before the bottle is placed on the support 3, although the seal itself may be moistened instead of the bottle, if desired, or the adhesive applied to the seal just before the sealing operation so that it is in condition to cause the seal to adhere to the mouth of the bottle when the sealing 115 120 125 130 operation takes place.

While I have shown and described my invention in a preferred form I am aware that various changes and modifications may be made without departing from the principles 5 of my invention.

What I claim as new and desire to secure by Letters Patent is:—

1. In a bottle sealing machine, a bottle support, a sectional head for pressing a 19 gummed paper seal or the like upon the mouth of a bottle on said support, means for effecting the pressure-applying operation of the head and means for withdrawing the head sections over and in rubbing contact 15 with the edge portions of the seal.

2. In a bottle sealing machine, a bottle support, a head having laterally and relatively movable sections forming a pressure face adapted to press a gummed paper seal 20 or the like against the edge of the mouth of a bottle on said support, means for relatively shifting said head and said support in line with the axis of the bottle to apply pressure to the seal and means for laterally 25 withdrawing the sections of said head over and in rubbing contact with the edge portions of the seal.

3. In a bottle sealing machine, a bottle support, a head comprising radially movable sections forming a pressure face adapted to clamp a gummed paper seal or the like against the edge of the mouth of a bottle on the support, means for relatively shifting said support and said head to apply and then 35 partially relieve the pressure on the seal and means for withdrawing the sections of said head over and in rubbing contact with the edge portions of the seal as the pressure is relieved.

4. In a device of the class described, the combination of a bottle support, a pressure applying member movable relatively to said support in the direction of the axis of a bottle thereon to press a seal against the bottle 45 mouth, a cushioning element interposed between the pressure applying face of said member and the bottle mouth during the pressure stroke and means for laterally withdrawing said element while in engagement 50 with the seal.

5. In a device of the class described, the combination with a bottle support, a head relatively movable to and from the mouth of a bottle on the support in the direction 55 of the axis of the bottle to press a seal upon the bottle mouth, radially movable sections of yielding material positioned in front of the pressure face of said head during the pressure stroke and means for withdrawing 60 said sections outwardly over and in contact with the edge portions of the seal.

6. In a device of the class described, the combination of a bottle support, a head having a pressure face for pressing a seal 65 against the edge of the mouth of a bottle on

said support, levers pivoted on said head, a series of radially movable sections of flexible material mounted on said levers and extending over the pressure face of said head, means for effecting the engagement of said 70 head with the seal on the bottle mouth with the sections in their innermost positions and means cooperating with said levers to shift the radially movable sections outwardly over and in rubbing contact with the edge portions of the seal.

7. In a bottle sealing machine, a bottle support, a head comprising radially movable sections for pressing a seal against the edge of the mouth of a bottle on the support, 80 means for effecting the pressure applying operation of the head with said sections in their innermost positions and means for withdrawing said sections outwardly while in engagement with the seal.

8. In a device of the class described, the combination of a yieldable bottle support, a pressure applying member adapted to engage the upper edge of the neck of a bottle on the support and depress the latter so as 90 to clamp a seal between the pressure applying member and the upper edge of the bottle neck, means for relaxing the pressure applying member so as to permit the support to recede to normal position, segmentary 95 cushioning means on said pressure applying member, and means for withdrawing said segmentary cushioning means radially from the top of the bottle as the pressure is relaxed.

9. In a device for applying a seal to the mouth of a bottle, the combination of a bottle support, means for applying pressure to the upper edge of the bottle neck comprising a pressure face composed of radially movable segments, means for projecting said pressure applying means with the segments in the innermost position and subsequently withdrawing same radially while engaged with the upper edge of the bottle neck.

10. In a device for applying a seal to the mouth of a bottle, the combination of a bottle holder, a head having a pressure face composed of segments, pivoted levers supporting the segments to permit swinging movement thereof, a member engaging said levers for moving same radially, a pair of cams co-operating to project the head and said member simultaneously toward a bottle on the holder and maintaining the segments in the innermost position, one of said cams being adapted to operate said member thereafter so as to withdraw the segments radially from the top of the bottle.

11. In a device for applying a seal to the mouth of a bottle, the combination of a yieldable bottle holder, a head having a plurality of oscillable members thereon carrying segments forming a pressure face, means for oscillating the levers so as to move the

segments radially, a pair of cams operable to simultaneously actuate the head and said means and thereby maintain the segments in the innermost position and project same against the upper edge of the neck of the bottle on the support and depress the bottle holder, means on one of the cams for relax-

ing the pressure on the bottle so as to permit return of the bottle holder to the normal position and maintain a diminished pressure on the bottle, and means on the other cam operable simultaneously to withdraw the segments laterally from the mouth of the bottle.

FRED C. AREY.
